UNITED STATES PATENT OFFICE.

SAMUEL K. DENNIS, OF CHICAGO, AND BERT R. BENJAMIN, OF OAK PARK, ILLINOIS,
ASSIGNORS TO INTERNATIONAL HARVESTER COMPANY, A CORPORATION OF NEW
JERSEY.

CHECKROW PLANTER.

Application filed May 21, 1927. Serial No. 193,204.

The check-row planting equipment of the present invention includes improvements in check wire anchors for use with a tractor drawn, high speed, check-row planter, which are cooperable to enable the user to accurately "check" (or plant the hills of corn in an entire field accurately at the apices of aligned squares) at a rate from two to three times greater than the rate of planting hereinbefore obtaining in the use of conventional horse drawn check-row planting equipment.

An object of the invention is to provide an improved check wire anchor capable of cooperating with a four-row tractor planter to produce accurate "checking" of corn.

The invention is illustrated by the accompanying drawings, in which:

Figure 1 is a side elevation of the check wire anchor located in a position substantially corresponding to operative position;

Figure 2 is a plan of the check wire anchor shown in Figure 1;

Figure 3 is a front elevation of the check wire anchor;

Figure 4 is a diagrammatic view illustrating the action taking place during the "checking" of a field;

Figure 5 is a diagrammatic view illustrating the first step in the method of using the illustrative equipment; and

Figure 6 is a detail diagrammatic view illustrating a step in the use of the illustrative equipment, subsequent to the step illustrated in Figure 5.

Referring to Figures 1, 2 and 3 of the drawings, the illustrative check wire anchor includes the reciprocable guide 1 straddling the usual end stake 2. The guide is preferably formed of a single rod bent to provide a loop 3, the parallel members 4, and the hooks 5. As clearly shown in Figure 2 of the drawings, the members 4 are forwardly convergent at a position indicated at 6. Forwardly of this position these members are substantially parallel and placed in proximity to each other. They are rigidly held in this position by a clamp 7 removably secured in position by the bolt 8.

Forwardly of the clamp 7 the ends of the members 4 are bent upwardly to form the hooks 5. These hooks are also upwardly divergent, as is clearly illustrated in Figure 3 of the drawings. This formation of the members 4 enables the check wire to be

readily secured to the anchor by inserting 55 the wire within the upwardly diverging hooks, the enlargement or button of the check wire engaging the hooks on the side toward the end stake 2.

For permitting necessary flexibility of the 60 anchor, so that it may adapt itself to various conditions obtaining at different periods during the use of the illustrative equipment, the end stake 2 is joined to the clamp 7 by yielding means herein shown as a coil 65 spring 9 preferably surrounding and enclosing the members 4. One looped end 10 of the coil spring receives the end stake, as clearly illustrated in Figures 1 and 2. The other looped end 11 of the coil spring is 70 placed over the forwardly converging parts of the clamp 7, the ends of which serve as abutments to lock the looped end 11 in operative position.

Figures 1 and 2 of the drawings illustrate 75 the relative positions of the parts of the anchor when the spring is under tension, this condition being normally created by the hooking of the check wire within the hooks 5 when the check wire is stretched 80 across a field to be planted. It will be evident that a decrease in the pull of the check wire will result in the movement of the hooks 5 toward the stake 2 by reason of the contractile effect of the spring 9. 85 Similarly, any increase in the pull of the check wire upon the anchor will result in the expansion of the spring 9 and the increasing of the distance between the stake 2 and the clamp 7. In the present invention 90 the practical maximum of the movement of the guide relative to the stake is regarded as about 6 to 8 inches during the checking operation.

During the operation of the illustrative 95 equipment an anchor is secured at each of the positions indicated at 12 and 13 in Figure 4 of the drawings, at 14 in Figure 5 of the drawings, and at 15 and 16 in Figure 6 of the drawings. When the user first takes the illustrative equipment to the field, an anchor is secured in the ground at a position corresponding to 14 in Figure 5. The planter is then driven across the field in the direction of the arrow 17 in Figure 5. An anchor is then placed at a position corresponding to that of 15 in Figure 6 of the drawings and the planter is driven in the direction of

arrow 18. This figure illustrates the first trip across the field during which actual planting of the seeds in the soil takes place. Figure 4 of the drawings illustrates conditions of the equipment during the starting of any trip across the field during the planting, check wire anchors being secured at positions 12 and 13.

Referring to Figure 4 of the drawings, 10 the planter is shown advancing in the direction of the arrow 45. The check wire 46 is anchored at positions 12 and 13 at the ends of the field. During such action it is necessary for the planter to move the check 15 wire transversely of the field a distance indicated by the line S-T. In doing so, the length P-S of the check wire is constantly being moved while the planter is in motion. Owing to the fact that the distance S-T is 20 substantially twice as great for four-row planting as it is for two-row planting, a considerably greater length of check wire must be moved by the planter a considerably greater distance. On account of the fact 25 that much of the check wire is lying on the ground, the work done by the planter in moving the check wire is considerably greater in four-row operation than in two-row. It is also to be appreciated that as the 30 length P-S of the check wire is being moved, that movement is taking place at much higher speed during the use of the present invention as compared to the customary two-row check-row planting equipment. Greater ground resistances are 35 encountered and greater forces are necessary to operate all of the second drop valves upon the planter. Furthermore, greater and more sudden impacts are delivered to the butts 40 tons on the check wire and to the check forks during the use of the equipment illustrated.

Referring to Figure 4 of the drawings, the 45 reference letter P represents the position of the operative check head just as the planter is starting a trip across the field. The letter R represents the position of the end stake securing the check wire at the end of the field from which the planter is moving. Q 50 represents the position to which the check head P has advanced when the planter is a substantial distance into the field, and O represents a point in the path of movement of the planter at the same distance from the 55 edge of the field as is the point R. Under these conditions the angle PRO is much greater than the angle QRO, and this difference is even greater at the time when the check wire is placed within the check head 60 P. This action takes place just after the planter is turned so that it faces in the same direction as it faces in Figure 4 of the drawings.

Again referring to the drawings mentioned 65 in the preceding paragraph, considerable

tension is placed upon the length of check wire R-P when the wire is placed in the check head P, and this tension is much greater in a four-row planter than in a two-row planter. This is due to many conditions, among which is the greater distance of the point P from the central line of advance of the planter. When the planter has reached the advanced position indicated at 70 Q, the increased tension on the check wire 75 at the position P has moderated and the check wire is no longer at such a sharp angle to the line of advance. This condition is representative of the problems involved in the making of check-row equipment within 80 the scope of the present invention.

While the invention has been described in relation to a particular structure, it is to be understood that it is not limited thereto but that it is susceptible of practice including 85 the use of structures coming within the scope of the appended claims.

What is claimed is:

1. A check-wire anchor comprising, in combination, an end stake, a guide longitudinally movable with respect to said stake and having portions straddling the stake, a check-wire retaining hook at one end of said guide, and a coil spring surrounding said guide having one end fixed to said stake, the 90 other end of the coil spring being fixed with relation to said guide.

2. A check-wire anchor comprising, in combination, an end stake, a movable guide having parts straddling the end stake, cooperating hook members at one end of said guide, a clamp secured to said guide near the hook members, a coil spring enclosing said guide and having one end substantially fixed with relation to said guide by said clamp, the other end of the coil spring being held in fixed position by the stake. 100

3. A check-wire anchor comprising, in combination, an end stake, a reciprocable guide formed of a single length of metallic 110 rod straddling said end stake, said rod having substantially parallel portions, hooks formed by the ends of the guide, means for holding the hooks in fixed operative relation and a spring extending from said means to the stake, one end of the spring being fixed with relation to the guide near said means and the other end of the spring being fixed with relation to the stake. 115

4. A check-wire anchor comprising, in combination, an end stake, a reciprocable guide movable with relation to the end stake and formed of a single length of metallic rod straddling the end stake, an upstanding hook formed by ends of the rod, a clamp secured to both sections of the rod in proximity to the hook, and a coil spring surrounding the guide and extending from the clamp to the stake, one end of the spring being anchored to the clamp and the other end to the stake. 120

5. A check-wire anchor comprising, in combination, an end stake, a guide longitudinally movable endwise with respect to said stake and having portions extending 5 around and straddling the stake, a check-wire retaining hook rigid and integral with the guide at one end of the latter, and a coil spring surrounding said guide and having one end held in fixed position by said 10 stake, the other end of the coil spring being fixed with relation to said guide.

6. A check-wire anchor comprising, in combination, an end stake, a movable guide having parts straddling and extending 15 around the end stake, a co-operating hook member formed integrally with the guide at one end of the latter, a clamp detachably secured to said guide near the hook members, a coil spring enclosing said guide and having one end substantially fixed with relation 20 to said guide by said clamp, the other end of the coil spring being held in fixed position by the stake.

7. A check-wire anchor comprising, in combination, an end stake, a reciprocable 25 guide formed of a single length of metallic rod straddling and extending around said

end stake, said rod having substantially parallel portions, hooks formed by bending the ends of the guide, a clamp for holding the hooks in fixed operative relation and a coil spring extending from the clamp to the stake, one end of the spring being fixed with relation to the guide near said clamp and the other end of the spring being fixed with relation to the stake. 30 35

8. A check-wire anchor comprising, in combination, an end stake, a guide reciprocably movable with relation to the end stake and formed of a single length of metallic 40 rod straddling and extending around the end stake, an upstanding hook formed by the bent ends of the rod, a clamp detachably secured to both sections of the rod in proximity to the hook, and a coil spring surrounding 45 the guide and extending from the clamp to the stake, one end of the spring being anchored to the clamp and the other end to the stake.

In testimony whereof we affix our signatures. 50

SAMUEL K. DENNIS.
